United States Patent [19]

Chow

[11] Patent Number: Des. 292,979

[45] Date of Patent: ** Dec. 1, 1987

[54] AUTOMATIC SEMICONDUCTOR WAFER TESTER

[75] Inventor: Marland Chow, San Jose, Calif.

[73] Assignee: Prometrix Corporation, Santa Clara, Calif.

[**] Term: 14 Years

[21] Appl. No.: 727,417

[22] Filed: Apr. 26, 1985

[52] U.S. Cl. D10/75; D10/46

[58] Field of Search ..... D10/46, 75, 77, 78, D10/81, 102; 324/73 R, 73 AT, 73 PC, 158 F

[57] CLAIM

The ornamental design for an automatic semiconductor wafer tester, as shown.

DESCRIPTION

FIG. 1 is a top and left front perspective view of an automatic semiconductor wafer tester showing my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof.

FIG. 1

FIG. 2

FIG. 3

FIG. 4

FIG. 5

FIG. 6
